UNITED STATES PATENT OFFICE.

GEORGE O. WALTON, OF EASTON, PENNSYLVANIA.

KEY-RING.

SPECIFICATION forming part of Letters Patent No. 586,407, dated July 13, 1897.

Application filed November 24, 1896. Serial No. 613,254. (No model.)

To all whom it may concern:

Be it known that I, GEORGE O. WALTON, a citizen of the United States, residing at Easton, in the county of Northampton, State 5 of Pennsylvania, have invented certain new and useful Improvements in Key-Rings; and I do hereby declare the following to be a full, clear, and exact description of the invention, such as will enable others skilled in the art 10 to which it appertains to make and use the same.

My invention relates to key-rings, and has for its object to provide a device of this nature which will be cheap of manufacture and 15 may be readily operated to apply and remove a key and one in which when a key is applied it will not be accidentally removed.

In the drawings forming a portion of this specification and in which like letters of reference indicate similar parts in the several views, Figure 1 is a sectional view of my device, showing the elements thereof in the first position which they assume when the key is being applied. Fig. 2 is a plan view showing 20 the positions of the elements after the inner ring has been removed to carry the key along the outer ring; and Fig. 3 is a view similar to Fig. 2, showing the elements of the ring in the same position as in Fig. 1 and illustrating 25 the means in which a key is finally arranged upon the ring.

Referring now to the drawings, in constructing a device in accordance with my invention I provide a broken ring *b*, on one side of the 30 gap *c* of which is an outward bend *d*, resulting in an inner recess *e*.

Arranged within the ring *b* is a second similar ring *f*, the gap *g* of which in one position is in alinement with the recess *e* in the outer 35 ring, while when the inner ring is moved to its opposite limit the inward bend *h* and resultant recess *i* are adjacent the corresponding positions *d* and *e* of the outer ring, as shown in Fig. 2. In order to maintain the 40 relative positions of the rings and to allow of oscillation of one within the other, I have formed in the ring *b* longitudinal slots *l* and *m*, in which play heads of screws or rivets *o* and *p*, securely fastened to the inner ring. 45 A third slot *r* is formed in the inner ring *f*, in which plays a screw or rivet *s*, securely fas-

tened in the outer ring. Thus it will be seen that as the inner ring is oscillated the rivets will play backward and forward in their respective slots, and not only will they limit 55 the extent of oscillation, but will prevent displacement of the parts.

The operation of my device, which is as follows, will be readily understood.

The parts being in the positions shown in Fig. 1, a key is entered through the opening *c* of the outer ring, the edge of the opening in the head thereof entering the recess *i* of the inner ring. By then holding the outer ring firmly and pressing the key in the direction 60 of the bend *d* the opening of the key will receive the ring *b* and the key will finally lie upon the bend *d*, as shown in Fig. 2. By then retaining the key upon the bend *d* and returning the ring to its former position the 65 key may be manipulated to pass from the bend and inclose both the inner and outer ring, as shown in Fig. 3. Thus it will be seen that it being necessary to conversely operate the ring to remove the key, and which requires manipulation of the elements of the 70 device, the key cannot leave the ring accidentally, but instead will be held securely thereon.

It will be readily understood that I may 75 vary the specific form and arrangement of the elements of my device without departing in any manner from the spirit of my invention and that I may use any material that may prove desirable in the manufacture of 80 the article.

Having thus described my invention, what I claim is—

1. A device of the class described comprising a plurality of open rings connected to permit oscillation of one within another, said rings having opposite bends arranged to be alternately alined with each other and with the openings.

2. A device of the class described comprising a plurality of open rings connected to permit oscillation of one within another, said rings having bends arranged to be alternately alined with each other and with the openings of the ring, and means for limiting the extent of oscillation.

3. A device of the class described comprising

ing a plurality of open rings adapted to oscillate one upon another, said rings having opposite bends arranged to be alternately aligned with each other and with the openings 5 in the rings, slots formed in the rings and rivets carried by the rings and adapted to play in the slots in their opposite rings.

In testimony whereof I affix my signature in presence of two witnesses.

GEORGE O. WALTON.
